(57) **CLAIM**

The ornamental design for a display panel with animated graphical user interface as shown and described.

DESCRIPTION

1. Display panel with animated graphical user interface

1.1 : Front view

1.2 : Front view in changed state 1

The broken lines showing a display panel form no part of the claimed design; the broken lines showing portions of the animated graphical user interface form no part of the claimed design.

The appearance of the transitional image sequentially transitions between the images shown in reproductions 1.1-1.2; the process or period in which one image transitions to another image forms no part of the claimed design.
